UNITED STATES PATENT OFFICE.

WALTER M. INGRAM, OF SUDBROOK PARK, MARYLAND, ASSIGNEE, BY DIRECT AND MESNE ASSIGNMENTS, TO THE SANITARY TEA BAGGING COMPANY, OF BALTIMORE, MARYLAND, A CORPORATION OF MARYLAND.

CARD-FEEDING MECHANISM.

Application filed July 15, 1925. Serial No. 43,889.

This invention relates to card feeding mechanisms and has for an object to provide means for feeding from a stack of cards the bottom card with new and improved action and co-actions.

A further object of the invention is to provide mechanism for maintaining a stack of cards in vertical position with a new and improved type of slide member for reciprocating beneath the stack of cards to remove from the bottom the lowermost card and feed it forwardly to a different position.

A further object of the invention is to provide in a stack holding chamber means for sustaining the stack of cards and at times lifting and at other times dropping said stack as the slide beneath reciprocates and in timed relation thereto.

A further object of the invention is to provide improved means for holding the projected card in contact with the slide as it is being moved to its required position.

With these and other objects in view, the invention comprises certain novel parts, elements, units, combinations, interactions, mechanical movements and functions as disclosed in the drawings together with mechanical and functional equivalents thereof as will be hereinafter more fully described and claimed.

In the drawings:

Figure 1 is a view of the improved card feeding mechanism in side elevation.

Figure 2 is a transverse sectional view taken on line 2—2 of Figure 1.

Figure 3 is a view of the mechanism partly in section with the slide positioned at its limit of movement opposite that shown at Figure 1.

Figure 4 is a plan view of the mechanism with transverse sectional view through the card stack chamber taken on line 4—4 of Figure 3.

Figure 5 is a transverse sectional view through the card stack chamber taken on line 5—5 of Figure 3.

Like characters of reference indicate corresponding parts throughout the several views.

The present invention embodies a card stack chamber which is in the form of an upstanding chute 10. In the drawings this upstanding chute or card chamber has been

shown as square or substantially square, but it is to be understood that the shape of this chamber is immaterial to the present invention and will be governed by the shape and proportions of the cards to be operated upon.

To the lower end of this card chamber cheek plates 11 are secured, provided with grooves 12 and 13 which in the normal position of the device will extend horizontally. In the groove 13 a slide 14 is mounted to reciprocate longitudinally in a normally horizontal plane and is provided with a tongue 15 which operates in said groove and a laterally extending flange 16.

Mounted in the groove 12 is also a slide plate 17 connected with the slide 12 by means of pins 18 extending rigidly upwardly from the slide 14 and engaging in slots 19 in said plate 17. The slide 17 is preferably covered with strips 20 of some friction increasing material as for instance rubber, leaving a longitudinal space intervening between said strips and over said slots 19.

Into this space a finger 21 is projected from a chamber 22 secured to the side of the chamber and adjustable by means of screws 23 in slots 24. This member 22 carries a rubber or other friction member 25 which extends under one shortened side of the stack chamber as indicated more particularly at Figure 3 and its inner surface substantially flush with the inner wall of said chamber. This member 25 is adjustable with the member 22 to provide for the necessary variation of spacing relative to the friction strips 20 to accommodate the sliding thereunder of one of the cards 26 in the stack. These cards 26 are held downwardly by added weight, as for instance the weight 26', so that they rest upon the strips 20 when the slide 17 is under said stack.

Auxiliary means for supporting the stack is also provided in a finger 27 which extends beneath the wall of the chamber at the side opposite the friction member 25 and is pivoted at 28. This finger 27 oscillates through a very limited arc upon its pivot 28 from the position shown at Figure 1 to the position shown at Figure 3. Such oscillation is accomplished by means of an arm 29 rigid and preferably integral

with the finger 27, said arm extending along beside and parallel with one of the cheek plates 11.

At its end opposite the pivot the arm 29 is provided with a foot 30 pivoted to the arm at 31 and the flange 16 of the slide 14 is provided with a notch 32 which co-acts with said foot in the manner herein-after more fully described.

19 The arm 29 is also provided with a lip 33 which extends beyond the pivot 28 opposite the finger 27 and in position to bear upon the card 26" as it is ejected from the stack, this lip 33 increasing the frictional engagement of said card with the rubber strips 20 to insure its proper and complete projection. At Figure 1 a member 34 with spring clip 35 is shown into which this card 26" is inserted by the movement of 29 the slide, it being understood, however, that this is merely to indicate conventionally a means for receiving the card and in no way a limitation upon or forming a part of the present invention.

25 In operation, the device assembled and arranged in the forward position shown at Figure 1, that is to say just delivering one card, and it is to be understood that the slide is now at its forward limit of movement and about to return. Of course, it is to be understood that some mechanical means for moving the slide is employed but it forms no part of the present invention. The slide 14 now being moved from position shown at 35 Figure 1 toward the position shown at Figure 3, the foot 30 bearing thereon will move from the position shown at full lines at Figure 1 to the position shown in dotted lines whereby through the weight of said foot 40 and the weight of the arm 29 the lip 33 will be raised and the finger 27 lowered. In the position shown at Figure 1, the finger 27 is raised to lift the stack of cards to enable the lower card propelled by the 45 slide to pass thereunder and at the initiation of return movement of the finger 27 the sustained stack is dropped. As there is a provision for lost motion between the slides 14 and 17, it is obvious that the lip 33 will raise and the finger 27 drop upon the first movement of the slide 14 and before the slide 17 starts to move. The starting of movement of the slide 17 from the position shown at Figure 1 by reason of the lower 50 card resting upon the rubber strips will cause the lower card to move with the slide 17 under the detaining member 25 and into engagement with the finger 21. This movement is sufficient to free the card from its 55 support upon the finger 27 and, when so positioned, the sliding members have reached their effective limit and any further movement simply causes the card to slide along on the strips 20 by reason of its engagement 60 against the finger 21.

At the limit of movement of the slide 14, the lower corner of the foot 30 drops into the slot 32, as shown at Figures 3 and 4. At these figures the sliding arrangement is shown at the extreme of movement. When the movement starts in the opposite or ejecting direction, the first action is to cause the foot to be turned to supporting position, that is to say the position shown in full lines at Figure 1, such turning movement being insured by the engagement of the heel of the foot in the slot 32. By reason of the formation of this foot with the long base, the slide may now slide under this foot while it is resting frictionally upon the flange 16.

The raising of the arm 29 by the movement of the foot 30 lifts the stack of cards 26 by the lifting of the finger 27 so that, when the slide 17 starts to move, the raised support thereon moves therewith under the finger which holds the cards out of position to effect any detention upon such movement. The card moves with the slide 17 forwardly to the position shown at Figure 1 and is pushed under the spring clip 35. This completes a cycle of operation and the return is as hereinbefore described, releasing the card thus inserted.

What I claim to be new is:

1. A card feeding apparatus comprising a chute, a slide operating in a plane perpendicular to the lower end of the chute, said slide presenting a bifurcated upper surface, means within the chute for supporting one end of the stack of cards in said chute, means to move said supporting means in timed relation to the action of the slide, occupying at one limit of its movement a position in the bifurcation and in its other limit above the surface of the slide, a stop positioned to limit the movement of a card in one direction, and a lip positioned to maintain a moving card in frictional engagement with the slide.

2. A card feeding apparatus comprising a card stack, a slide moving perpendicular to the lower end of said stack, a sliding member carried by said slide and connected therewith by a lost motion mechanism, a finger positioned to limit the movement of cards on said sliding mechanism in one direction, a lip positioned to bear upon the card moving in the opposite direction, and means to raise and lower said lip in timed relation to the reciprocation of said slide.

3. A card feeding mechanism comprising means for maintaining cards in vertical stack, a finger inserted into said stack and adapted to support the stack, means carried by the slide for raising and lowering the finger in timed relation to the reciprocation of the slide, a feeding mechanism carried by the slide and connected therewith by a lost motion connection, and a lip operated by the finger operating mechanism

adapted to bear upon the card on said feeding mechanism.

4. A card feeding mechanism comprising means for maintaining cards in a vertical stack, a compound slide operating beneath the stack, one part of which moves between the wider limits of reciprocation than the other, means carried by the lesser moving part for frictional engagement with the 10 lower card of the stack, means within the

stack for supporting the stack independently of the sliding mechanism, a lip without the stack proportioned to bear upon a card on said lesser moving slide, and means for operating the finger and lip in timed relation ¹⁵ with the sliding of the greater moving slide part.

In testimony whereof I affix my signature.

WALTER M. INGRAM.
